UNITED STATES PATENT OFFICE.

JOHN R. COCHRANE, OF NEWARK, NEW JERSEY, ASSIGNOR TO THE BIGELOW CARPET COMPANY, OF NEW YORK, N. Y.

DESIGN FOR CARPET.

SPECIFICATION forming part of Design No. 23,487, dated July 24, 1894.

Application filed June 28, 1894. Serial No. 516,029. Term of patent 3½ years.

To all whom it may concern:

Be it known that I, JOHN R. COCHRANE, a subject of the Queen of Great Britain, residing at Newark, in the county of Essex and State of New Jersey, United States of America, have invented and produced a new and original Design for a Carpet, of which the following is a specification, reference being had to the accompanying drawing, forming a part thereof, which represents a face view of a carpet in which the new design is embodied.

The invention relates to a design to be worked into or upon surfaces such as carpets and similar fabrics, and it consists in the novel configuration of figures, as is herein shown and claimed.

The design consists of the body A and border B. The body A is decorated with arched panels in shaded effect, containing flowers of the tulip type, and placed between a branch of flowers of the rose type, and a second branch of flowers of the same type combined with flowers of the thistle type. Sprays of

rose-buds, roses and small flowers are interposed between the main figures. The border 25 B is decorated with spray-surrounded panel figures described in the decoration of the body A, and between these figures a chain of small flowers is arranged, a bunch of flowers of the rose type being above the chain; foliated figures are likewise located between the main or panel figures, and a crenelated dado appears at the outer margin of the border.

I claim—

1. In a design for a carpet, the body A, substantially as shown.
2. In a design for a carpet, the border B, substantially as shown.
3. The design for carpets, consisting of the body A and the border B, substantially as 40 shown.

JOHN R. COCHRANE.
